Term of patent 14 years

(Cl. D33—19)

FIG.1

FIG.2

FIG.3

FIG.4

FIGURE 1 is a front-quarter perspective view of a bedside console cabinet showing my design;

FIGURE 2 is a right side elevational view of the same; and

FIGURE 3 is a plan view.

FIGURE 4 is a front-quarter perspective view of the cabinet showing the control housing element in extended position.

The back side, which is not illustrated, is substantially flat and plain.

The dominant features of my design reside in those portions shown in full lines on the drawing.

The telephone shown by means of dotted lines is for illustrative purposes only.

I claim:

The ornamental design for a bedside console cabinet, substantially as shown and described.
